UNITED STATES PATENT OFFICE.

LOUIS A. SCHMIDT, OF BROOKLYN, NEW YORK, ASSIGNOR TO R. HOE AND CO., OF NEW YORK, N. Y., A CORPORATION OF NEW YORK.

FOLDING MECHANISM.

Application filed May 24, 1921. Serial No. 472,176.

To all whom it may concern:

Be it known that I, LOUIS A. SCHMIDT, a citizen of the United States, residing at Brooklyn, county of Kings, and State of 5 New York, have invented certain new and useful Improvements in Folding Mechanism, fully described and represented in the following specification and the accompanying drawings, forming a part of the same.

10 This invention relates to certain improvements in folding mechanisms.

In certain folding mechanism, particularly rotary folders in which the sheet is taken on a folding cylinder by suitable sheet taking 15 devices and advanced to folding off rolls into which it is tucked by a folding blade, a variation in the speed of the cylinder causes an irregularity in the folding off of successive sheets. As for instance, with a rotary cylinder 20 at starting or running at slow speeds the leading end of the sheet, that is the end taken by the sheet taking devices, is not advanced past the tucking blade by the sheet taking devices quite far enough with the result that 25 when the tucking blade acts to fold the sheet the tail end of the sheet will lap over the head end thus producing an irregular fold. On the other hand, when the cylinder is being driven at high speeds the throw of the 30 cylinder causes the sheet to be advanced too far past the tucking blade with the result that the head end of the sheet laps over on the tail end thus producing an irregular fold.

The especial object of the present invention 35 is to provide a folding mechanism in which there are provided means for effecting a relative change between the sheet path and the folding mechanism as the speed at which the sheets advance may vary, so that 40 successive sheets will be folded at the same point, as for instance on a transverse central line, irrespective of their speeds.

A further object of the invention is to produce such a construction in which this is 45 automatically effected by the speed of the sheet advancing means so that the mechanism will adjust itself to fold the sheets evenly at whatever the speed the folder may be running, either at the start off or when 50 it is running at its full capacity.

A further object of the invention is to produce a simple and economical construction for effecting this, particularly adapted for rotary folders and in which the mechanism

and arrangement of the folder, as ordinarily 55 designed need not be changed so that the device may be added to folders already built as well as in folders of new construction.

With these and other objects not specifically referred to in view, the invention 60 consists in certain novel parts and combinations, a preferred form of which is shown in the accompanying drawing with which the invention will be described in detail, and the novel features then pointed out in the claims 65 hereunto annexed.

In these drawings—

Figure 1 is an end elevation, partly broken 70 away showing the improved folding mechanism.

Figure 2 is a sectional view taken on the line 2—2 of Fig. 4.

Figure 3 is a view similar to Fig. 2 showing the parts in different position; and

Figure 4 is a side view partially in section and partially broken away, the view being taken on the line 4—4 of Fig. 2.

Referring now to these drawings, the invention has been illustrated as employed in connection with a printing machine in which sheets are cut from a printed web and folded. It will be understood, however, that the invention is applicable for folding cut sheets supplied from any suitable source.

Referring now to these drawings 1 indicates a frame work of any suitable character for supporting the parts, the frame work being arranged at the folder end of a printing machine, not illustrated, a former 2 being shown over which a web, indicated by the letter W, is led, between the usual drawing off rolls 3, 4 to give the web a longitudinal fold.

In the construction illustrated this web W has sheets cut therefrom by suitable mechanism. While this cutting mechanism may vary, there is provided a cylinder 5, having the usual cutting knives 6, this cylinder co-operating with a cylinder 7 provided with the usual cutting woods 8. The cylinder 5 is shown as half the diameter of the cylinder 7, and the latter cylinder is provided with a pair of cutting woods, a sheet thus being cut from the web at each revolution of the cylinder 5 and each half revolution of cylinder 7. The cylinder 5 may also act as a collecting cylinder if desired, being provided with sheet taking devices, such as pins

9, operated by arms 10 on rock shaft 11 suitably controlled by a cam roll 12 in the usual manner.

The drawing off rolls 3, 4 act as usual in this type of machine to determine the length of the sheet to be cut, these rolls forwarding a sufficient amount of the web to provide a sheet of the required length, and the speed of these rolls is so timed with relation to 10 the cutting mechanism that the cutters operate after a predetermined length of web has been forwarded, the cut always taking place after this predetermined sheet length has been fed past the cutters.

15 The folding mechanism by which the sheets are given a transverse fold may be of various characters, and the sheets may be advanced to this folding mechanism in various ways. In the particular construction 20 illustrated, the folder is shown as a rotary folder, the cylinder 7, before referred to, being provided with sheet taking devices, as pins 13, 14, and a rotary tucking blade 15 co-operating with a pair of folding off rolls 25 16, 17. When collecting is desired one set of the pins of cylinder 7 are silenced, as is usual.

As this rotary cylinder 7 is started up the 30 speed of the cylinder is relatively slow. This results in the leading end of the sheet not being taken quite far enough at the time the tucking blade acts to make the fold with a result that the sheet is not folded on its transverse center line and one end overlaps 35 the other and an irregular fold produced. The same is true when the cylinder is speeded up to high capacity, only in this case the sheet is carried by momentum of the cylinder too far beyond the tucking blade at 40 the time it makes the tuck so that the head end of the sheet overlaps the tail and irregular folded products are produced.

In accordance with the invention means 45 are provided for effecting a change in the sheet path relative to the folding off blade so that the folding off blade will always act at the same point in the sheet irrespective of the sheet speed. While this may be done in various ways, in the best construction this 50 is accomplished by varying the length of the sheet path, the folding mechanism per se maintaining their regular positions, and by such construction a very simple way of effecting the result is provided. In the particular construction illustrated, therefore, 55 means are provided for lengthening or shortening the path the sheet travels beyond the tucking off point, and as illustrated, this is done by increasing or decreasing the 60 diameter of the cylinder so that the head end of the sheet will have a longer or shorter path to travel before the tucking blade takes it off. In the specific mechanism illustrated for effecting this, the cylinder is provided 65 with two flattened surfaces or flats marked

18, 19 and co-operating with these flattened portions are movable members which may be arranged to be moved inside the line of the flats or outwardly beyond them to the extent desired. These movable members may be 70 of various types, and moved in various ways for increasing or decreasing the cylinder diameters. In machines embodying the invention in its best form, however, these means will be such as to effect the movement of the members automatically in accordance with the increase or decrease of the cylinder speed, the members being moved to lengthen the sheet path at low cylinder speed and to shorten the sheet path at high cylinder speed. As illustrated the members are in the form of fingers 20, 21. The number of these fingers may of course be varied, but as shown there are provided two sets of four fingers each. These fingers are hooked 85 shaped, as indicated at 22 and the shanks of the hooks are secured on rock shafts 23, one of the rock shafts being provided for each set of fingers, and suitably mounted in bearings 90 in the heads 24 of the cylinder. 95

These rock shafts 23 are operated to move the fingers by a governing mechanism controlled by the speed of the cylinder. As shown, this governing mechanism includes arms 25 mounted on the shafts, which arms carry weights in the form of balls 26. As the cylinder rotates and its speed varies these balls are thrown in or out by centrifugal force and rock the shafts to move the fingers corresponding to the cylinder speed. 100

In the position of the parts shown in Fig. 2 it is assumed that the cylinder is operating at slow speed and consequently the sheet path is the longest, the fingers being in their outermost position, and the governors are controlled so that at this slow speed the shafts will be rocked to cause the arms to assume this position. While this may be accomplished in various ways, in the particular construction illustrated, the arms 105 25, before referred to, carry blocks 27 having short pins 28, these blocks and pins forming seats for one end of springs 29, and the other ends of these springs bear against flanged studs 30 suitably secured 110 in the cylinder wall. These springs tend to throw the arms inward and thus rock the shafts 23 to move the fingers 20 outwardly the length of the sheet path. In order that the shafts shall not be rocked too far, adjustable stops 31 are provided mounted in brackets 32 secured to a flange 33 on the head of the cylinder, the side of the blocks 27 opposite the springs taking 115 against these stops. 120

With the construction described, a very simple mechanism has been provided for varying the length of the sheet path with respect to the folding off point, so that a sheet will be folded on a given line and an 125 130

even fold given to the sheet irrespective of the cylinder speed, and furthermore, this variation of the sheet path is automatically effected according to the speed at which the cylinder is driven.

The folding blade is operated as is usual in rotary folders, being driven by a gear 34 on one end of the blade shaft 35 on which the folding blade is mounted, this gear 34 meshing with an internal gear 36 suitably fixed in the frame of the machine. The folding cylinder is driven from a shaft 38 suitably journaled in the machine frame, this shaft being driven in any suitable manner from a power shaft of the machine. This shaft at one end carries a gear 39 which meshes with a gear 40 on the shaft 41 by which one of the folding off rolls, as the roll 16, before referred to, is driven. These two rolls are intergeared to rotate together in opposite directions by gears 42 one of which is shown in Fig. 4. The shafts 43 which carry the pins 13, 14, before referred to, are supported in the heads 24 of the cylinder and are operated in any suitable manner, as by a cam 44 secured in the side frames before referred to.

From the folding rollers 16, 17, the folded sheets are delivered in any suitable manner as by a fly delivery 45 from which they are removed by belts 46.

If desired, a second web may be associated with the web W, such web being indicated by the letter W', being passed into the folder over a guide roll 47 supported in brackets 48 supported from the frame of the machine, the associated webs being cut by the mechanism before referred to and folded, or if desired collected and the collected products folded. In the best constructions suitable web guides 49, 50 will be provided located below the sheet paths around the folding cylinder, these guides being suitably supported in the side frames of the machine.

While the invention has been shown and described in its preferred form, it will be understood that various changes and variations may be made in the specific construction of the parts, and in the specific construction for varying the length of the sheet path, and the invention as defined in the appended claims will be understood to include such variations of the structure and arrangements of the parts.

What I claim is:

1. The combination of means for advancing sheets at different speeds, folding mechanism, and means for effecting a relative change between the sheet path and folding mechanism to cause the fold to take place at the same point in successive sheets irrespective of their speed.

2. The combination of means for advancing sheets at different speeds, folding mech-

anism, and means actuated by speed variation of the advancing means for effecting a relative change between the sheet path and folding mechanism whereby the fold is caused to take place at same point in successive sheets irrespective of their speed. 70

3. The combination of means for advancing sheets at different speeds, folding mechanism, and means for varying the length of the sheet path to cause the fold to take place at the same point in successive sheets irrespective of their speed. 75

4. The combination of means for advancing sheets at different speeds, folding mechanism, and means actuated by speed variation of the advancing means for varying the length of the sheet path to cause the fold to take place at the same point in successive sheets irrespective of their speed. 80

5. The combination of means for advancing sheets at different speeds, folding mechanism, and means for lengthening the sheet path when the advancing means is operating slowly, and for shortening the sheet path when operating at high speeds 90 to cause the fold to take place at the same point in successive sheets irrespective of their speed. 85

6. The combination of means for advancing sheets at different speeds, folding mechanism, and means actuated by speed variation of the advancing means to lengthen the sheet path at slow speeds and to shorten the sheet path at high speeds to cause the fold to take place at the same point in successive sheets irrespective of their speed. 95 100

7. The combination of a rotary carrier, sheet holding devices thereon, a folding mechanism, means for varying the length of the sheet path on the carrier as the carrier speed varies, and means for controlling the path length varying means. 105

8. The combination of a rotary carrier, sheet holding devices thereon, a folding mechanism, means for varying the length 110 of the sheet path on the carrier as the carrier speed varies, and means actuated by the carrier speed for controlling the path length varying means.

9. The combination of a rotary carrier, 115 sheet holding devices thereon, a folding mechanism, means for varying the length of the sheet path on the carrier, and a centrifugal governor controlling the path length varying means. 120

10. The combination of a rotary carrier, sheet holding devices thereon, a folding mechanism, means for varying the diameter of the carrier to vary the length of the sheet path, as the carrier speed varies, and means for controlling the varying means. 125

11. The combination of a rotary carrier, sheet holding devices thereon, a folding mechanism, means for varying the diameter of the carrier to vary the length of the 130

sheet path as the carrier speed varies, and means operated by the carrier speed for controlling the varying means.

12. The combination of a rotary carrier, sheet holding devices thereon, a folding mechanism, means for varying the diameter of the carrier to vary the length of the sheet path, and a centrifugal governor for controlling the varying means.

13. The combination of a rotary carrier, sheet holding devices thereon, a folding mechanism, a member movable beyond the surface of the carrier for varying the length of the sheet path as the carrier speed varies, and controlling means for the member.

14. The combination of a rotary carrier, sheet holding devices thereon, a folding mechanism, a member movable beyond the surface of the carrier for varying the length of the sheet path as the carrier speed varies, and controlling means operated by the carrier speed for the member.

15. The combination of a rotary carrier, sheet holding devices thereon, a folding mechanism, fingers movable beyond the surface of the carrier for varying the length of the sheet path, a rock shaft on which the fingers are mounted and a centrifugal governor for rocking the shaft.

16. The combination of a rotary carrier, sheet holding devices thereon, a folding mechanism, a member movable beyond the surface of the carrier for varying the length of the sheet path as the carrier speed varies, a controller for the member, and means for causing the controller to normally hold the member in its out position.

17. The combination of a rotary carrier, sheet holding devices thereon, a folding mechanism, a member movable beyond the surface of the carrier for varying the length of the sheet path, a controller for the member, and a spring for causing the controller to normally hold the member in its out position.

18. The combination of a rotary carrier, sheet holding devices thereon, a folding mechanism, a flat on the carrier, a member movable from a position within the line of the flat to a position beyond the surface thereof to vary the length of the sheet path, and a controller for the member actuated by the speed of the carrier.

19. The combination of a rotary folding

cylinder having a tucking blade, sheet holding devices on the cylinder, a member movable beyond the surface of the cylinder to vary the length of the sheet path with relation to the tucking blade as the cylinder speed varies, and a controller for the member actuated by the cylinder speed.

20. The combination of a rotary folding cylinder having a tucking blade, sheet holding devices on the cylinder, flats on the cylinder, swinging fingers movable beyond the flats to vary the length of the sheet path with relation to the tucking blade, rock shafts on which the fingers are mounted, centrifugal governors connected to the rock shafts, and springs for rocking the shafts to normally cause the fingers to be in their out position.

21. The combination of means for forwarding a web, means for cutting sheets therefrom, means for advancing the cut sheets at different speeds, folding mechanism, and means for effecting a relative change between the sheet path and folding mechanism to cause the fold to take place at the same point in successive sheets irrespective of their speeds.

22. The combination of means for forwarding a web, means for cutting sheets therefrom, means for advancing the cut sheets at different speeds, folding mechanism, and means actuated by speed variation of the advancing means for effecting a relative change between the sheet path and folding mechanism whereby the fold is caused to take place at the same point in successive sheets irrespective of their speed.

23. The combination of a rotary carrier, sheet holding devices thereon, a folding mechanism, means for varying the length of the sheet path on the carrier, and means rotating with the carrier for controlling the path length varying means as the carrier speed varies.

24. The combination of a rotary cylinder to which sheets are forwarded, a folding mechanism, means for varying the length of the sheet path on the cylinder, and means operating independently of the folding mechanism for controlling the path length varying means.

In testimony whereof, I have hereunto set my hand.

LOUIS A. SCHMIDT.
